UNITED STATES PATENT OFFICE.

WILLIAM TINSLEY JONES, OF SPOKANE, WASHINGTON.

BRUSHES FOR VACUUM-CLEANERS.

1,038,383.

Specification of Letters Patent.

Patented Sept. 10, 1912.

Application filed September 25, 1911. Serial No. 651,240.

To all whom it may concern:
Be it known that I, WILLIAM T. JONES, a citizen of the United States, residing at Spokane, in the county of Spokane and State of Washington, have invented certain new and useful Improvements in Brushes for Vacuum-Cleaners; and I do hereby declare the following to be a full, clear, and exact description of the invention, such as 5 will enable others skilled in the art to which it appertains to make and use the same, reference being had to the accompanying drawings, and to the letters and figures of reference marked thereon, which form a 10 part of this specification.

This invention relates to certain new and useful improvements in brushes for vacuum cleaners and it has for its object the provision of brushes disposed upon opposite 20 sides of the vacuum slot, the brushes being adapted to be automatically raised or lowered so as to cause one or the other brush to contact with the floor as needed, while the brush upon the opposite side is raised out 25 of engagement with the floor so as not to afford an obstruction to the passage of dust through the vacuum slot.

To this end and to such others as the invention may pertain, the same consists in 30 the peculiar construction and in the novel combination, arrangement and adaptation of parts, all as will be more fully herein-after described, shown in the accompanying drawings and then specifically defined in 35 the appended claims.

The invention is clearly illustrated in the accompanying drawings which, with the numerals of reference marked thereon, form a part of this specification and in which:—

40 Figure 1 is a side elevation of a vacuum cleaner constructed in accordance with my invention. Fig. 2 is an end view of the device, and Fig. 3 is a central vertical section.

Reference now being had to the details 45 of the drawings by numeral, 1 represents the suction head of a vacuum cleaner provided with the usual vacuum slot 2 and socket member 3 for attachment of the handle. Suitably mounted upon opposite sides of the 50 vacuum slot 2 are brushes 4, 4, the said brushes extending the entire length of the suction head and adapted to be moved vertically within guideways 5, 5.

The brushes 4, 4 are carried by the lower 55 ends of arms 6 which, at their upper ends, are pivotally connected to the outer ends

of the cross heads 7. At each end of the suction head the said cross head is pivoted at its longitudinal center at 8 and at the lower end the arm 9 is provided with teeth 10 adapted to mesh with a pinion 11. Said pinions 11 are fastened one to each wheel 17 which are journaled upon stub shafts 18 fastened to the opposite ends of the head. 60 12, 12 are spiral springs connecting projecting portions of the cross head with pins 16 upon the suction head.

From the foregoing description, the operation of the device will be understood and is as follows:—As the operator pushes the 70 device forward, the wheels 17 will be rotated and, as the teeth upon the lower ends of the arms 9 of the cross heads are in mesh with the pinions which rotate with the wheels, will cause the said cross heads to 75 tilt upon their pivots, thus throwing down the brush toward the handle or at the rear of the vacuum head, while the other brush will be raised from contact with the surface against which the wheels contact. In the 80 event of the head being moved backward, a reverse movement will be imparted to the wheels and cause the upper brush to be thrown down and the lower one raised.

It will be noted that, by pulling back 85 the handle in the opposite direction, the position of the brushes will be reversed so that the brush traveling in the rear of the vacuum slot will at all times be in contact with the surface being swept while the 90 brush in advance of the slot will at all times be free.

Having thus fully described my invention, what I claim to be new and desire to secure by Letters Patent is:—

95 1. A vacuum cleaner comprising a suction head having an elongated slot at the bottom thereof, brushes mounted one on each side of said slot, T-shaped levers pivoted to said head, connections between the same and said 100 brushes, and means for actuating said levers to actuate the brushes as the cleaner is moved backward or forward, as set forth.

2. A vacuum cleaner comprising a suction head having an elongated slot at the bottom 105 thereof, brushes mounted one on each side of said slot, T-shaped pivotal levers pivoted to said head, connections between the levers and said brushes, the lower end of each lever being serrated, wheels journaled upon the 110 head, pinions rotating with the wheels and in mesh with said serrations, as set forth.

2

3. A vacuum cleaner comprising a suction head having an elongated slot at the bottom thereof, brushes mounted one upon each side of said slot, T-shaped levers pivotally mounted upon the ends of the head, springs fastened to the two oppositely extending arms of each of said T-shaped levers, pins fastened to the head to which said springs are secured, the lower end of each lever having teeth formed therein, wheels journaled upon the head, pinions fixed to said

wheels and in mesh with said teeth, and connections between each brush and the ends of the oppositely extending arms of the lever, as shown and described.

15

In testimony whereof I hereunto affix my signature in the presence of two witnesses.

WILLIAM TINSLEY JONES.
